UNITED STATES PATENT OFFICE.

JOHN M. BEAVERS, OF WACO, TEXAS.

GIN-SAW-FILING MACHINE.

SPECIFICATION forming part of Letters Patent No. 592,045, dated October 19, 1897.

Application filed August 18, 1896. Serial No. 603,131. (No model.)

To all whom it may concern:

Be it known that I, JOHN M. BEAVERS, a citizen of the United States, residing at Waco, in the county of McLennan and State of Texas, have invented a new and useful Gin-Saw-Filing Machine, of which the following is a specification.

My invention relates to gin-saw-filing machines, and has for its object to provide a simple and efficient apparatus whereby the teeth of the gin-saw may be uniformly and quickly filed, the parts of the mechanism being adjustable to secure the desired bevel of the teeth and suit saws having their teeth arranged at different intervals.

Further objects and advantages of this invention will appear in the following description, and the novel features thereof will be particularly pointed out in the appended claims.

In the drawings, Figure 1 is a perspective view of a saw-filing machine constructed in accordance with my invention. Fig. 2 is a longitudinal section of the same. Fig. 3 is a detail view in perspective of the file-carrier and attached parts. Fig. 4 is a detail view of the guide and slide detached.

Similar numerals of reference indicate corresponding parts in all the figures of the drawings.

The frame 1 of the machine is constructed to support the driven shaft 2, which is provided with operating devices, such as a crank 3, and is connected, by means of a gear 4 and an intermeshing pinion 5, with a crank or driving-shaft 6. Projecting forwardly from the frame are supporting-arms 7, the front portions of which are arranged in parallel planes and are adapted to rest upon spacing-blocks between contiguous gin-saws, and respectively upon opposite sides of the saw to be filed. Arranged between said arms is a swinging or adjustable guide consisting of side bars 8 and terminal yokes 9, the rear end of the guide being attached to a transverse rock-shaft 10, which is terminally mounted in the supporting-arms 7, and the front end of said guide being supported by a stirrup 11, also connecting the supporting-arms and serving to brace the same laterally.

Mounted in the guide above described is a slide 12, which is capable of direct recipro-

catory movement in a plane coincidental with that of the guide, and pivotally mounted upon said slide, by means of a fulcrum pin or screw 13, is a file-carrier 14. Mounted upon this file-carrier are the file-supporting arms 15 and 16, the former consisting of a spring-arm bolted or otherwise attached to one side of the carrier and projecting in front thereof with an attached file 17, and the latter being pivotally mounted upon the carrier by means of an upstanding pin 18 and also supporting a file 19. This pivotal arm is held in operative relation with the saw which is being filed by means of an actuating-spring 20, which extends around the fulcrum-pin 18 and bears at one end against the looped rear extremity of the arm, while its other end bears against a tension device consisting of a slide 21, slotted, as at 22, and engaged by a set-screw 23.

The pivotal file-supporting arm is arranged above the plane of the spring-arm and is designed to operate upon the saw at an interval of three teeth from the latter, whereby a uniform dressing of the teeth may be secured, and the under side or lower edge of the pivotal arm is inclined downwardly toward its front end, as shown at 24, contiguous to a pivotal adjusting-arm 25, which is mounted upon the carrier 14 and is designed to be swung forwardly or rearwardly at its free end to vary the vertical position of the file carried by said arm. The object of this adjustment is to adapt the machine to varying intervals between the teeth of different saws, and the arm consisting of a cross-sectionally flat bar in rear of the beveled portion 24 it is obvious that it will yield vertically and will be held by its resilience in contact with the adjusting-arm in all positions of the latter. Thus the file-carrying arms are arranged in different transverse or horizontal planes and in intersecting vertical planes, and in practice I prefer to construct the arm 16 of a flat strip having its rear portion in a horizontal and its front portion in a vertical plane, said horizontal and vertical portions being connected by an intermediate twist, which thus provides the inclined or beveled surface for co-operation, as above described, with the adjusting-arm 25. In other words, the twisting of the strip forming the arms causes one edge thereof to incline downwardly toward the front or

outer extremity of the arm, thus providing means for varying the interval between the transverse planes of the carriers.

The carrier is connected by means of a pitman 26 with the crank of the crank-shaft 6, the latter being fitted with a balance-wheel 27 to insure uniform movement of the parts. The front end of the pitman extends through an opening 28 in a plate-spring 29, which is secured to the upper side of the carrier and is perforated at its front end to receive the fulcrum pin or screw 13, said screw also passing through a corresponding perforation in the pitman. The front end of the pitman is downwardly convexed to form a rocker to bear upon the upper side of the carrier, whereby an angular adjustment of the guide upon which the slide 12 is mounted provides for the change of direction of movement of the carrier without affecting the operativeness of the pitman, the perforation in the front extremity of the latter being slightly larger than the fulcrum-screw to allow sufficient play to prevent cramping. The plate-spring 29 prevents the fulcrum-screw from becoming detached or loosened by jarring.

The front ends of the file-supporting arms are turned inwardly or toward the saw to form trip-fingers 30, which are adapted to bear against opposite sides of a saw when the file-carrier is approaching the limit of its rearward stroke, in order to momentarily disengage the files from the saw-teeth, and said inturned extremities of the supporting-arms are perforated, as shown at 31, to receive the points 32 of the files, the rear extremities or shanks of the files being secured to the supporting-arms by means of clamps 33, or their equivalents.

From the above description it will be seen that the resilient or yielding file-supporting arms hold the files yieldingly in contact with the saw and operate at such intervals as to insure a uniform position of both files with relation to the several teeth, and in order to vary the bevel of the teeth it is only necessary to adjust the front end of the guide by means of a screw 34, which is mounted in the stirrup in which said guide rests. To vary the relative positions of the file-supporting arms to suit the intervals between the teeth of the saw, I have provided the adjusting-arm 25 in contact with the pivotal supporting-arm, the latter being of spring metal whereby it is adapted to yield vertically and is held by its resilience in contact with the adjusting-arm. It will be understood that the pivoting of the file-carrier at an intermediate point provides for the lateral swinging or yielding thereof to insure the uniform dressing of opposite sides of a tooth.

In order to secure the desired pressure of the arms 7 upon the spacing-blocks between the saws, and insure uniformity of such pressure, I preferably employ a weight 35, or its equivalent.

In order to hold the saw from accidental

rotation during the filing of a tooth, I employ no positive lock, such as a stop pawl or dog, but depend upon the frictional contact of the supporting-arms 7 upon the gin-shaft, or upon the spacing-blocks, as above described, which are arranged between contiguous saws. These supporting-arms thus form brakes, and the frictional contact thereof is varied to produce the desired tension by means of the above-described weight 35.

As in other machines of this class, the files accomplish the major portion of their operation during the forward stroke, during which the crossed supporting-arms are gradually spread or swung laterally in opposite directions until the limit of the forward stroke is reached. The pivotal mounting of the file-carrier, which allows transverse or horizontal swinging movement thereof, provides for equalizing the pressure of the files upon opposite sides of a tooth, and inasmuch as the frictional contact of the opposite files varies with the extent of contact of the files with the saw, and as the extent of contact, or the surface of a tooth which is in contact with a file, varies as the tooth is filed (by reason of the file cutting away the material of the tooth in order to produce upon the latter a surface parallel with itself) it is obvious that the frictional contact of the files with a saw-tooth increases at each successive stroke of the files. In other words, during the first stroke of the files upon a tooth the force (tending to turn the saw against the opposing friction caused by the brake-arm 7) due to frictional contact of the files with the tooth, and the pressure of the files due to the tension of the spring 20 may be, for instance, three pounds, owing to the fact that but a small area of the tooth is in contact with each file; but during the second forward stroke of the files the area of the tooth exposed to contact by the files has been increased by the cutting away of a portion of the tooth, and I have estimated that the force exerted upon the tooth (tending to advance the saw against the resistance offered by the brake-arms 7) will be approximately nine pounds, or the square of the force exerted during the first stroke. Now if the weight, which is employed to act as a brake, by causing downward pressure of the arms 7 upon the gin-shaft or spacing-blocks, is twenty pounds, it will be found that even at the end of the second stroke the force exerted by the files will be insufficient to overcome the pressure of the brake-arms and advance the saw. Hence the files will again return to their initial position preparatory to a third stroke. During this third stroke the force exerted by the files upon opposite sides of the tooth will be still greater than during the second stroke, due to the reason above explained, and I have estimated, in view of experiments, that the force exerted during a third stroke is the cube of the pressure exerted during the first stroke, which, in this case, would amount to twenty-seven

pounds, and hence would be sufficient to overcome the resistance of the brake-arms and advance the saw. Inasmuch as the frictional contact of the files with the teeth is less during the backward than during the forward stroke, whereas the resistance offered by the brake-arms is constant, it will be seen that the files will return to their initial position without affecting the saw. As the files approach the limit of their backward stroke the extremities of the trip-fingers 30 come in contact with opposite surfaces of the saw and thus remove the files from contact with the teeth. The forward feeding movement of the saw, as upon the third stroke of the files above described, necessarily elevates the front ends of the supporting-arms, and hence tilts the guide upon the transverse rock-shaft 10 as a center, but when the files are drawn back and the extremities of the trip-fingers come in contact with the side surfaces of the saw the frictional contact of said trip-fingers is insufficient to hold the file-supporting arms in this elevated position in opposition to the gravity of the guide, slide, and supporting-arms, and hence said parts drop to their normal position, limited by the contact of the guide with the extremity of the adjusting-screw 34, and the files start forward in contact with the next tooth, or rather the teeth respectively succeeding those upon which the files had previously been operating. Thus the advance or forward feeding movement of the saw is due to the frictional contact of the files with the opposite sides of the saw-teeth, the force exerted by reason of such frictional contact varying as the filing of the teeth progresses, whereby in case one tooth requires a greater amount of filing than another in order to produce the same beveled surface for contact with and in the planes of the files, a greater number of strokes will be applied to that tooth. The saw will not be advanced till the tooth which is being operated upon has been filed to produce a bevel having a certain area, that area being sufficient to produce a frictional contact equal to or greater than the resistance offered by the friction-brake which is employed to hold the saws normally in a state of rest. Therefore the resistance offered to the forward movement of the saws is constant, as also is the tension of the pressure of the files toward the saw, and in order to provide for controlling the operation of the mechanism when the files vary in sharpness, I have found it necessary to establish an approximate relation between the constantly-acting yielding means for resisting the forward motion of the saw and the tension of the files. Hence with sharp files the tension or the pressure thereof upon the saw should be light, while the weight which operates the brake-arms should be proportionately heavy, whereas when the files are dull the tension thereof or the pressure thereof toward the saw should be increased, while the weight

which actuates the brake-arm should be proportionately decreased.

Various changes in the form, proportion, and the minor details of construction may be resorted to without departing from the spirit or sacrificing any of the advantages of this invention.

Having described my invention, what I claim is—

1. A gin-saw-filing machine having a reciprocating file-carrier provided with laterally-yielding file-supporting arms, capable of swinging movement in the plane of the saw in contact with which the files are arranged, and constantly-acting means for yieldingly holding the saw normally at rest, the saw being adapted to be advanced by the force exerted by reason of the frictional contact of the files with the teeth, against the resistance offered to the forward movement of the saw, when the filed surfaces of the teeth have reached a predetermined area, substantially as specified.

2. A gin-saw-filing machine having a reciprocating file-carrier provided with laterally-yielding file-supporting arms, adapted for swinging movement in the plane of the saw in contact with which the files are arranged, brake-arms and constantly-acting means for maintaining said arms in frictional contact with the gin-shaft, the saw being adapted to be advanced, in opposition to the resistance offered by the brake-arms, by the frictional contact of the files with the beveled surfaces of the saw-teeth, said frictional contact of the files being insufficient to advance the saw until the teeth have been filed sufficiently to produce beveled surfaces having predetermined areas, substantially as specified.

3. A gin-saw-filing machine having a guide mounted to swing in a plane parallel with a saw, means for limiting the return movement of the guide, a file-carrier mounted upon the guide for reciprocating movement and carrying laterally-yielding file-supporting arms, brake-arms, and constantly-acting adjustable means for maintaining the brake-arms in contact with the gin-shaft to yieldingly hold a saw against forward feeding movement, said constantly-acting means being adjustable to vary the tension of the pressure of said brake-arms to correspond with the lateral tension of the file-supporting arms, substantially as specified.

4. A gin-saw-filing machine having a guide mounted for swinging movement in the plane of a saw and yieldingly held in its normal position, a transversely-swinging file-carrier mounted for reciprocation upon said guide, spring-actuated file-carrying arms on the carrier, means for adjusting the tension of the actuating-spring of one of the arms, and constantly-acting means for yieldingly holding a saw in a position of rest, substantially as specified.

5. A gin-saw-filing machine having a reciprocable carrier, spring-actuated file-carrying arms supported by the carrier and adapted to bear in opposite directions against the 5 teeth of a saw, means for varying the tension of the pressure of said file-carrying arms toward the saw, and constantly-acting variable means for yieldingly holding a saw in a position of rest, the saw being adapted to be advanced against the resistance offered by said 10 constantly-acting means by the frictional contact of the files with the saw-teeth, substantially as specified.
6. A gin-saw-filing machine having a reciprocatory file-carrier, a laterally-yielding spring-metal file-supporting arm attached to the carrier to operate upon one side of the 15 teeth of a saw, a second file-supporting arm pivotally mounted upon the carrier and provided with an actuating-spring, an adjustable tension device for varying the tension of the actuating-spring, and means for operating the carrier, substantially as specified.
7. A gin-saw-filing machine having a reciprocatory carrier, laterally-yielding file-supporting arms mounted upon the carrier to operate in different transverse planes, one of 20 said arms being vertically yielding and provided with a beveled under surface, an adjusting-arm pivotally mounted upon the carrier in operative relation with said beveled surface, whereby the interval between the planes of the files may be varied by bringing the arm in contact with the beveled surface 25 at different points, and operating devices for the carrier, substantially as specified.
8. A gin-saw-filing machine having a slide mounted in a suitable guide, a file-carrier pivotally mounted for lateral swinging movement upon 30 said slide and provided with horizontally-swinging file-supporting arms disposed in intersecting vertical planes, and adapted to be arranged at their front ends upon opposite sides of the plane of a saw, whereby said arms are adapted to yield laterally by the movement of said carrier, and means for communicating reciprocatory 35 movement to the carrier, substantially as specified.
9. A gin-saw-filing machine having an angularly-adjustable guide arranged to swing in a vertical plane, means for varying the inclination of said guide, a slide mounted in 40
- the guide, a file-carrier mounted upon the slide and provided with file-supporting arms, 55 and means for communicating reciprocatory movement to the carrier, substantially as specified.
10. A gin-saw-filing machine having forwardly-extending supporting-arms adapted 60 to be arranged upon opposite sides of a saw to rest upon contiguous spacing-blocks, a guide provided at its rear end with a rock-shaft terminally mounted in said arms, a stirrup connecting said arms in front of the rock-shaft to support the front end of the guide, adjustable means for limiting the downward movement of the guide, a slide mounted in the guide, a file-carrier mounted upon the 65 slide and provided with file-supporting arms, 70 and means for communicating reciprocatory movement to the carrier, substantially as specified.
11. A gin-saw-filing machine having a slide mounted in a suitable guide, a file-carrier fulcrumed for lateral swinging movement upon 75 said slide, laterally-yielding file-supporting arms on the carrier, a crank-shaft and means for communicating rotary motion thereto, and a pitman connecting the crank-shaft with the 80 carrier and attached to the carrier coaxially with its fulcrum, substantially as specified.
12. A gin-saw-filing machine having a slide mounted in a suitable guide, a file-carrier fulcrumed for lateral swinging movement upon 85 said slide, laterally-yielding file-supporting arms on the carrier, a crank-shaft and means for communicating rotary motion thereto, a pitman connecting the crank-shaft with the carrier and arranged at its front end coaxially 90 with the same, the carrier being provided with a fulcrum-screw extending through the front end of the pitman, and a plate-spring attached to the carrier and bearing upwardly against the head of said screw, said spring 95 being provided with an opening through which the front end of the pitman extends, substantially as specified.
- In testimony that I claim the foregoing as my own I have hereto affixed my signature in 10 the presence of two witnesses.

JOHN M. BEAVERS.
